[57] CLAIM

The ornamental design for a seat, as shown and described.

DESCRIPTION

FIG. 1 is a front perspective view of a seat showing our new design in the form of a sofa;

FIG. 2 is a right side elevational view of FIG. 1, the left side being a mirror image thereof;

FIG. 3 is a fragmentary front elevational view of FIG. 1;

FIG. 4 is an enlarged sectional view of a stitching design shown on the backrest of FIGS. 1 and 3; and,

FIG. 5 is a front perspective view of a seat showing our new design in the form of an armchair.

The rear view which has not been shown is plain and unornamented.

The broken lines shown in all views represent stitching.

FIG. 1.

FIG. 2.

FIG. 4.

FIG. 3.

FIG. 5.

UNITED STATES PATENT AND TRADEMARK OFFICE
CERTIFICATE OF CORRECTION

PATENT NO. : Des. 350,034
DATED : August 30, 1994
INVENTOR(S) : Natuzzi et al.

It is certified that error appears in the above-identified patent and that said Letters Patent is hereby corrected as shown below:
